ARTICLE

Moses N. Esses, Brooklyn, N. Y.

Application April 12, 1950, Serial No. 9,164

Term of patent 7 years

(Cl. D92—26)

To all whom it may concern:

Be it known that I, Moses N. Esses, a citizen of the United States, residing at Brooklyn, in the county of Kings and State of New York, have invented a new, original, and ornamental Design for Flocked Furniture Scarf or Similiar Article, of which the following is a specification, reference being had to the accompanying drawing, forming part thereof.

In the drawing, Fig. 1 shows diagrammatically a view of a flocked furniture scarf or similar article showing my new design. Fig. 2 shows on a large scale an end of the flocked furniture scarf or similar article.

I claim:

The ornamental design for flocked furniture scarf or similar article, as shown.

MOSES N. ESSES.
